UNITED STATES PATENT OFFICE.

DEWITT C. CREGIER, OF CHICAGO, ILLINOIS.

PRESSURE-REGULATOR FOR WATER-SUPPLY MAINS.

SPECIFICATION forming part of Letters Patent No. 257,557, dated May 9, 1882.

Application filed August 12, 1881. (No model.)

To all whom it may concern:

Be it known that I, DEWITT C. CREGIER, city engineer, residing in Chicago, Cook county, in the State of Illinois, have invented certain new and useful Improvements relating to Pressure-Regulators for Water-Supply Mains for Cities and Towns, of which the following is a specification.

I provide a supply of water under a high pressure which shall be additional to and independent of the ordinary supply. The water for my system may be of a different quality.

The water from my system may be used to sprinkle streets, gardens, lawns, &c., to supply fountains for ornamental purposes, and, if the quality is proper, for washing, supplying bathing establishments, and manufactories for various purposes; but it is more especially designed for two great uses in which a superior pressure is desirable—extinguishment of fires and the actuating of elevators and other machinery requiring small powers. I provide for maintaining a high and equable pressure on my entire system without requiring a reservoir or stand-pipe.

My apparatus occupies but little space, and is largely automatic in its adaptation to the various conditions.

The accompanying drawings form a part of this specification, and represent what I consider the best means of carrying out the invention.

Figure 1 is a vertical section through my device for equalizing the pressure. Fig. 2 is an elevation of the same. The elevation is mainly at right angles to the plane of section in Fig. 1; but the lower end of Fig. 2, represented as detached, is turned so as to stand in the same position as in Fig. 1, to better show the construction at that point. Fig. 3 is a vertical section through one of the devices for utilizing the pressure of the secondary system. Fig. 4 is an elevation of the forcing and equalizing means on a small scale.

Similar letters of reference indicate like parts in all the figures.

The ordinary water-pipes or system of water-distribution are indicated by W. They are supplied with water at a reasonable pressure, either from a river at sufficient elevation or by pumping or otherwise. The pipes for my water sys-

tem may be laid parallel to or even in contact with the same.

A are the boilers; B, the stack; C, a steam-cylinder, and D a pump. These parts may be of any ordinary construction and arrangement; but it is essential that the furnaces and boilers shall have the capacity for generating a large amount of heat and supplying liberal quantities of steam in cases of emergency, as when several fires occur simultaneously, and also that the furnaces and boilers, by banking the fires or otherwise, be capable of maintaining the heat in the boilers with but a little generation of steam, and without much consumption of fuel when but a small quantity of water is required, as during ordinary nights and Sundays. I make these operations partly automatic.

B' is a damper in the stack, and B² a rod connected to a lever controlling the same. By operating this rod the draft in the furnaces may be largely controlled.

C' is a throttle-valve or adjustable cut-off or expansion and gear, and C² is a rod connected thereto. By operating this rod C², the consumption of steam in the engine, and consequently the rate of working the engine and the rate of pumping, may be varied between wide limits.

E is the pipe which conveys the water from the pump D to supply the city.

To the pipe E, near the pump, I provide an upright casing, F, having a stuffing-box, F', around the top and an annular ledge or internal flange, F², around the bottom. Within this plays a hollow cylindrical plunger, G, closed at the top and open at the bottom. This plunger, properly loaded, serves in two ways: First, it rises and sinks with fluctuations in the ratio of the supply to the demand for water; and, second, its hollow interior, tightly closed except at the bottom, where it is entirely open, serves as an air-chamber by imprisoning a quantity of air and allowing the dividing-line between the air and the water to pulsate or rise and sink rapidly with momentary fluctuations in pressure due to the intermittent action of the pump and analogous causes. Care is taken to supply air through a small cock in the suction-pipe of the pump or otherwise, so as to keep the interior of G

always nearly filled, and thus to allow the plunger and its contents to serve with a large amount of elastic action.

The loading of the plunger G is effected 3 through separate weights G², which may be inserted and removed at pleasure in the open-topped carriage G'. This carriage is bolted on the top of the plunger, and is guided by slides F³, of which I provide four, arranged 10 as shown, connected to the casing F by arms F⁴, and united at the top by a transverse framing, F⁵.

It will be seen that when the water is consumed in the entire city at precisely the same 15 rate as it is supplied by the pump the plunger G will remain stationary; but the air imprisoned therein will expand and contract as the pump alternately passes its point of maximum delivery and its minimum delivery or dead-point. The supply of water from the pump to the casing F will be variable or intermittent; but the flow from the casing F to the city will be constant and the pressure nearly uniform. When the consumption in the entire city exceeds the supply by the pump the pulsations in the water due to the strokes of 20 the pump will continue to be extinguished, as before, by the elastic action of the air in the plunger G; but the general or mean pressure 25 under the plunger being less than the gravity of the load on the latter, it will sink. When the consumption is less than the supply by the pump the plunger will rise.

H is a bell-crank lever turning on a fixed 35 center, h, and carrying an adjustable weight, H', on its horizontal arm. The upright arm connects to the rod B², which operates the damper B' in the stack and controls the intensity of the fire. It also operates the rod C², 40 which controls the consumption of steam in the engine, and induces the engine, and consequently the pump, to change its speed the moment the lever H is changed in position. The horizontal arm of H rests on the rim of 45 the carriage G'. Whenever the plunger G rises, indicating that the pump is working in excess of the power required, it lifts the weight H' and shifts the rods B² C², so that the engine consumes less steam, and the draft in the 50 furnaces is less, so as to produce less steam in the boilers. So soon as the consumption of water is in excess of the pumping, the plunger G sinks, causing the lever H to sink, and consequently changing the position of the rods 55 B² C² in the opposite direction, giving more steam to the engine and more force to the fire. A stop, F⁶, arrests the motion of the lever H when it has descended to the extent which 60 will develop the maximum power of the apparatus, and the plunger may descend its full extent, performing its other functions of equalizing the flow without influencing the steam by any motion while it is in a low position; but so soon as the pumping has been sufficiently 65 quickened to raise the pressure throughout the city, and from its minute diminution again to the proper standard, the carriage G'

again rises into contact with the lever H, and reduces the consumption of steam and the motion of the engine and pump. I believe 70 that the control of the engine by this automatic arrangement will be complete; but the control of the fires in changing from extreme conditions will require the active assistance of one or more attendants. Experience will decide whether the change from a small power to the full power of all the boilers and back again shall be best effected by alternately spreading and banking the fires in some or all the furnaces or by kindling and extinguishing 80 the fires in certain furnaces. Leaving those, and many other questions of judgment, I will describe my provisions for calling attention to the conditions which require labor.

I is a double pulley, or a pulley wide enough 85 to carry two belts. It is mounted on a fixed center, h, and turned by a belt, I', leading from a small pulley on the main shaft of the engine. J is a pulley mounted on a center carried on the lever H. It is turned by a belt, J', leading 90 from the pulley I. J² are pins projecting axially from the pulley J.

K is a hammer-head carried on a spring-arm, K', mounted on the fixed frame-work. The arm K' projects beyond the head K, and 95 its end is bent at a right angle, as indicated at K².

When the apparatus is working at or near the proper speed and the steam is properly controlled by the lever H the latter stands in 100 such a middle position that the pins J² traverse around the bent end of the arm K' without touching it. The pulley J may be made large or small and the pin or pins J² made to describe a large or small circle, as required; but 105 the proportions must be such that when the action of the pump is much in excess, and the lever H ascends too high, the pins J² will strike the bent end of the arm K' and spring the hammer away from the bell and suddenly liberate it, inducing a smart stroke. This is 110 repeated at the passage of each pin J². When the reverse conditions obtain, and the lever H is held too low, as on the breaking out of a fire, and the sudden opening of one or more hydrants reduces the pressure under the plunger G, the pin or pins J² will at each passage strike 115 the bent end of the arm K' and induce a striking of the bell P by the hammer in a sufficiently different manner to be readily recognized by 120 the attendants—that is to say, the hammer K will be moved against the bell and held there a moment, sufficiently to produce a partially-deadening effect on the sound of the bell. In 125 the action under these conditions the hammer will be alternately pressed against the bell by direct force and liberated, the flexure of the free end of the spring-arm K' being sufficient to allow the motion of J². Under both conditions the bell will sound distinctly; but there 130 will be a recognizable difference between the positive stroke due to excessive speed and the recoil stroke due to insufficient speed.

The high pressure exerted by the water in

my system will work elevators and other small powers at any reasonable height in the city. It will force the water up through permanent systems of fire-pipes with which many modern 5 manufacturers and other large buildings are provided. It will supply water with more than ordinary facility and afford great assistance to the action of steam fire-engines and hand-engines. It will also in many or all portions 10 of the city supply water directly from hydrants under sufficient pressure to be available by simply attaching a hose without imparting to the water any further power than is due to the pressure of the mains. I make this last mode 15 of operation especially available by providing especial hydrants in those vicinities where the expense is warranted, which have provisions for a supply of hose in the immediate vicinity 20 of the hydrant. Any properly-authorized party running to the hydrant with proper facilities for opening can let on the water and make immediately available a sufficient length of hose to extend to the point desired and throw a stream immediately with the full force due to 25 the high pressure in the street-mains.

L is a hydrant, and L' the delivery-nozzle thereof. These may be of any ordinary character, but preferably of a style adapted for very easy and rapid engagement of the hose.

30 M is a reel turning on fixed bearings, and inclosed in a case, N, constructed under the sidewalk adjacent to the hydrant.

N' is a cover secured by a fastening corresponding to that on the hydrant, and operating with the same wrench or key. The reel M is equipped with a hand-wheel easily reached from above. In case of fire, the cover N' is unlocked and thrown back, the reel M partially rotated, if necessary, to bring up the end 35 of the hose, and the hose seized, drawn out, and coupled to the hydrant, and drawn off from the reel and extended to the point desired. The water is now let on by the operating of the hydrant, and the watchman alone 40 may hold the hose and extinguish a fire of considerable dimensions without waiting for the slower response which the fire department will make to the alarm which he has meanwhile given.

45 The hose should preferably be fabric alone, woven sufficiently close to be tight without rubber or perishable material. There will be plenty of time and help to thoroughly dry it, and insure its most favorable condition for endurance 55 for a long period before it is again wound up on the reel and inclosed, as before.

I esteem it important to guard against shocks when the plunger rises or sinks too far.

R is a spring attached in the position represented, and extending across so as to gently arrest the ascent of the carriage G' when it tends to rise too high.

60 T indicates two or more springs bolted on the under side of the carriage G', and arranged 65 to strike against the fixed framing below and

gently arrest the descent when the carriage G' tends to descend too far.

There is always more or less leakage through a stuffing-box. Any air accumulating more than sufficient to fill the hollow plunger G will 70 sink the level of the water for a moment below the base of G; but such excess of air will soon escape through the stuffing-box F' and allow the water again to rise to the bottom of the hollow plunger; but the air within the hollow plunger G is differently conditioned. It is sealed by the water. The water immerses the lower edge of G and rises within it to variable heights, according to the momentary changes of the pressure due to the action of the pump and 80 valves. It cannot escape through the open bottom. It is sealed against any access to the stuffing-box.

Modifications may be made in many of the details of the apparatus. Some of the parts 85 may be used without the others.

What I have termed the "carriage" G' may be of greater or less diameter. The air-chamber in the plunger may be extended upward so as to occupy a portion of the interior of the 90 carriage, and correspondingly increase the elastic action of the air on the surface of the water within the plunger. The means of guiding the carriage may be varied.

I can vary the forms and proportions of the 95 parts which effect the automatic regulation and the calling the attention of the attendant to an excessive elevation or depression of the plunger.

The junction of the pipe E to the plunger- 100 case F may be enlarged and rounded.

I believe that such water may be used with some success in my system conjointly with the pipes W for carrying fresh and pure water. There is no objection to the use of pure fresh 105 water for my system where it can be obtained.

I can provide a pipe (not represented) controlled by a cock or valve, delivering water into the carriage G' to fill the interstices between the several weights G² and to flow to any required height above the entire series of removable weights until the carriage G' is nearly full. A stop-cock or siphon may be provided to facilitate the drawing out of such water when required.

115 By making the carriage G' large enough the removable load in the carriage may be water alone; but I prefer for general convenience the removable weights G² of iron, lead, or other dense solid material, in convenient sizes for ready introduction and removal, and using the water, if at all, as a means for adding small increments thereto.

I propose to make the duplex system of water-supply and my peculiar hydrant L, reel N, 125 and their connections the subject of a separate application for patent.

I claim as my invention—

1. In a system for supplying water from a pump or analogous forcing means, the plunger 130

G, made air-tight at the top and sides and sealed with water at the bottom, in combination with means for depressing it with a yielding force, and with the case F, stuffing-box F', and 5 pipe E, as herein specified.

2. The carriage G', open at top, and plunger G, open at bottom, in combination with each other and with the removable weights G², guides F³, pipe E, and pump D, as herein specified.

3. In combination with a pipe, E, and means for forcing water therethrough, the loaded hollow plunger G, bell P, hammer K, and means J², actuated by the engine for operating the 15 hammer, and actuating devices H for automatically bringing the operating means into and out of action as the plunger G rises and sinks, as herein specified.

4. In combination with the engine C, pump

D, pipe E, and loaded hollow plunger G, the 20 lever or movable piece H, operating the rods B² C² to control the speed of the pump, substantially as herein specified.

5. In combination with a lever, H, actuated by the rising and sinking of the hollow plunger 25 G, the pulley I and actuating-belt I', the pulley J and actuating-belt J', and pins J², hammer K and bell P, arranged for joint operation, as herein specified.

In testimony whereof I have hereunto set 30 my hand, at Chicago, Illinois, this 2d day of August, 1881, in the presence of two subscribing witnesses.

DEWITT C. CREGIER.
